UNITED STATES PATENT OFFICE.

LAURENT EMILE MARIE TREVOUX, OF PETIT-QUEVILLY, FRANCE, ASSIGNOR TO LA SOCIÉTÉ ANONYME DE PRODUITS CHIMIQUES ETABLISSEMENTS MALETRA, OF PETIT-QUEVILLY, FRANCE.

PROCESS FOR THE PRODUCTION OF ACETALDEHYDE FROM ACETYLENE.

No Drawing.

Application filed May 31, 1921. Serial No. 473,803.

To all whom it may concern:

Be it known that I, LAURENT EMILE MARIE TREVOUX, citizen of the Republic of France, and resident of Petit-Quevilly, France, (post-office address Petit-Quevilly, Seine-Inférieure), have invented a new and useful Process for the Production of Acetaldehyde from Acetylene, which improvements are fully set forth in the following specification.

This invention relates to a process for the production of acetaldehyde from acetylene. For the synthetic production of acetaldehyde when a current of acetylene is passed over a mercuric salt in an acid medium, the activity of the mercuric catalyst rapidly diminishes and the absorption of the acetylene becomes slower in proportion as the reduction of the mercuric salt progresses, and stops completely when the mercuric salt is reduced to the state of a greyish powder. At this moment, whatever method is employed, it is necessary to regenerate the mercuric salt by oxidation.

In the process which is described in my copending application for United States Patent Serial No. 368,439, filed March 24, 1920, the activity of the catalyzing agent is maintained by adding to the mercury constituting such agent or reduced mercury an oxidizing substance, such as ferric oxide or another suitable oxidizing agent.

This addition allows of prolonging the action of the mercury indefinitely without it being necessary to regenerate same. When the oxidizing agent is exhausted the liquid is decanted, and suitable proportions of ferric oxide and sulphuric acid are added to the residual grey powder. From time to time the ferroso-ferric salt of the reaction liquid is tested by means of potassium permanganate and the ferric oxide is renewed when necessary.

Although the preparation of ferric oxide is relatively cheap, instead of renewing it every time with fresh liquid containing ferric oxide, use is made of a reoxidized liquor coming from a previous reaction. The reoxidation of the ferrous salt into ferric salt can be effected either by boiling with nitric acid or preferably by electrolysis.

This last method is employed in the present application.

The use of electrolysis for regenerating certain substances in the synthetic production of aldehyde and acetic acid is well known, the various procedures being based on the same principle, namely, subjecting the acetylene to anodic oxidation by the use of an acid electrolyte containing mercury. In reality the oxidation by electrolysis in the interior of the catalyzer itself counteracts the reaction and prevents the formation of the metal-organic compound which generates the aldehyde. Moreover only small amounts of aldehyde and acetic acid are obtained. It is for this reason that these processes have not been employed in practice and that up to the present as far as I know it has not been possible to effect directly the synthesis of acetic acid without first producing the aldehyde and thereafter oxidizing same.

Neither has it been thought possible that, by regenerating the ferric salt within the catalyzer by the electrolytic operation, a practical result can be obtained. It is necessary for the oxygen carriers to be added to the reaction liquid in such a way that without preventing, retarding or diminishing the formation of aldehyde they are adapted, if suitably controlled, to act on the ferroso-ferric salt by constantly maintaining an excess of ferric oxide in the reaction liquor.

On the other hand it is not possible without great inconvenience to directly electrolyze the residual reaction liquor, because this does not merely contain a ferrous salt only. The residual reaction liquor (which is slightly coloured brown after the acetylene has been passed therethrough) always contains, in addition to the ferrous salt, a variable small amount of acetaldehyde (uncondensed) as well as the mercuric salt in solution. If the residual liquor of reaction is directly electrolyzed in a suitable electrolyzer, for example consisting of a receptacle of lead with a cathode of the same metal, it will be noticed that, after regeneration, a large deposit of lead salt is produced. Moreover, the cathode has become amalgamated and partly disintegrated.

1. A part of the acetaldehyde has been transformed by the electrolytic oxidation into acid. This acid combines with peroxide of lead and sulphuric acid, in solution in the ferrous liquor, to form lead sulphate and

free acetic acid which combines afresh with the lead peroxide and so on. The acetic acid thus plays the rôle of a catalyzer and a small content of acetic acid is sufficient to start the 5 reaction.

2. The cathode is attacked by reason of the fact that the residual reaction liquor contains a little dissolved mercury salt.

10 Although mercury sulphate is very slightly soluble, the small amount of the salt in solution is electrolyzed and deposits on the cathode, which it amalgamates. The same inconvenience occurs with a cathode of copper or other metal.

15 According to the present invention, the operation is effected in the following way. Acetaldehyde is prepared until the catalyzer is exhausted and the ferric salt has been reduced. Thereupon the residual reaction liquor is separated by decantation. This liquor contains ferrous salt a little dissolved mercury salt and acetaldehyde.

20 The aldehyde is first removed by heating or preferably by evacuation. If, in order 25 to remove the aldehyde, the liquid were heated to a relatively high temperature, part of said aldehyde would be resinified, and would yield tars. It is therefore preferable to operate in vacuo at a temperature 30 below 50° C., so as to eliminate the aldehyde without polymerization. The aldehyde vapours are recovered by suitable means, such as condensation or in the form 35 of stable paraldehyde.

40 Thereupon the ferrous liquor from which the aldehyde has been removed is brought into contact with iron filings which completely precipitate the mercury. According to the working temperature employed, the mercury sulphate is transformed more or less quickly into mercury, the reduction being complete in about two hours at 70° C. The mercury is deposited at the bottom of the receptacle and the liquid is decanted. 45 The liquor thus contains only ferrous sulphate in sulphuric acid solution and it is ready to be electrolyzed.

The above series of operation may be reversed.

50 The electrolyzer consists preferably of a lead receptacle with lead electrodes. It is essential to maintain the density of the current as uniformly as possible throughout the whole of the bath. With a current of four 55 volts and of a density of 0.3 amps. per square centimetre at the cathode, and of 0.0107 amp. per square centimetre at the anode, it is possible to re-oxidize at a temperature of 30° C., a liquor containing 28.4 grammes 60 of ferrous oxide per litre.

The liquor thus regenerated is poured back on to the residual grey mercury powder, acetylene being then introduced. From the moment the first bubbles come off, the 65 absorption takes place and the production

of acetaldehyde proceeds as intensely and rapidly as if a new catalyzer of mercury and ferric oxide were used.

What I claim and desire to secure by Letters Patent is:—

70 1. The process for the regeneration of the residual reaction liquors obtained in the synthetic production of acetaldehyde from acetylene, in the presence of metallic mercury in an acid medium, and of a substance 75 adapted to maintain the catalyzing action of the mercury, which comprises removing the acetaldehyde and mercury from said liquor and submitting the remaining liquor to an oxidizing action.

2. The process for the regeneration of the residual reaction liquors obtained in the synthetic production of acetaldehyde from acetylene, in the presence of a mercury catalyzing agent in an acid medium, and of 80 a substance adapted to maintain the catalyzing action of the mercury, which comprises removing the acetaldehyde by the employment of vacuum at a temperature below 50° C., thereupon removing the mercury from said liquor and submitting the remaining liquor to an oxidizing action.

85 3. The process for the regeneration of the residual reaction liquors obtained in the synthetic production of acetaldehyde from acetylene, in the presence of a mercury catalyzing agent in an acid medium, and of a substance adapted to maintain the catalyzing 90 action of the mercury, which comprises eliminating the acetaldehyde, thereupon precipitating the mercury from said liquor by means of iron filings, decanting the liquor, and subjecting the decanted liquor to an 95 oxidizing action.

100 4. The process for the regeneration of the residual reaction liquors obtained in the synthetic production of acetaldehyde from acetylene, in the presence of a mercury catalyzing agent in an acid medium, and of a substance adapted to maintain the catalyzing 105 action of the mercury, which comprises eliminating the acetaldehyde by the employment of a vacuum at a temperature below 50° C., thereupon precipitating the mercury from said liquor by means of iron 110 filings at a temperature not exceeding about 70° C., decanting the liquor and subjecting the decanted liquor to an oxidizing action.

115 5. The process for the regeneration of the residual reaction liquors obtained in the synthetic production of acetaldehyde from acetylene, in the presence of metallic mercury, sulfuric acid, and of a ferric compound, which comprises removing the acetaldehyde and mercury from said liquor and 120 oxidizing the ferrous compound to ferric compound.

125 6. In the synthetic production of acetaldehyde from acetylene in the presence of metallic mercury in an acid medium and of 130

- a substance adapted to maintain the catalyzing action of the mercury, regenerating the residual reaction liquor, which comprises removing the acetaldehyde and mercury 5 from said liquor, subjecting the remaining liquor to an oxidizing action, and thereupon returning said regenerated liquor to the process to be used again in the synthetic production of acetaldehyde.
- 10 7. In the synthetic production of acetaldehyde from acetylene in the presence of metallic mercury, sulfuric acid, and of a ferric compound, regenerating the residual reaction liquor, which comprises removing
- the acetaldehyde and mercury from said 15 liquor, oxidizing in the remaining liquor the ferrous compound to ferric compound, and thereupon returning said liquor containing regenerated ferric compound to the process 20 to be used again in the synthetic production of acetaldehyde.

In testimony whereof I have signed this specification in the presence of two subscribing witnesses.
